UNITED STATES PATENT OFFICE

RICHARD E. RUSDEN, OF PROVIDENCE, RHODE ISLAND, ASSIGNOR TO THE TEXTILE-FINISHING MACHINERY COMPANY, A CORPORATION OF RHODE ISLAND

DYE JIG

Application filed November 14, 1931. Serial No. 574,999.

This invention relates to a dye jig for use in connection with the finishing of textile material or for like use, and has for one of its objects to provide a construction with an independent simplified drive for each tank.

Another object of this invention is the provision of a construction in which an electric motor may be utilized for independently driving each jig.

Another object of this invention is the provision of a dye jig construction in which the jigs will each have an independent drive mounted completely upon each jig to cause each jig to be more accessible and permit the operator to freely walk completely around each tank if desired.

A further object of this invention is the provision of a construction which will be quiet in operation and one which will have a minimum vibration and wear upon the parts.

A still further object of this invention is the provision of a control means which may be operated from either side of each tank and in which the control of the different feed rolls will be simultaneous.

With these and other objects in view, the invention consists of certain novel features of construction, as will be more fully described, and particularly pointed out in the appended claims.

In the accompanying drawings:

Fig. 1 is an end view of one of the tanks with my improved driving means thereon.

Fig. 2 is an end view of a portion of the superstructure over the tank, illustrating the clutch or control means for the roll in its association with the driving gears.

Fig. 3 is a section on line 3—3 of Fig. 2.

Fig. 4 is a detailed view partly in section of the clutch and the control collar for operating the clutch.

Fig. 5 is a perspective skeleton view of the control means for operating the clutches for the feed rolls.

In the operation of dye jigs it has been usual to connect the feed rolls of a series of dye jig tanks to a common operating drive shaft extending longitudinally along a length of tanks by such means as bevel gears

or the like for operating the different feed rolls and to control the operation of each feed roll by a suitable clutch mechanism. It has been customary to use considerable additional gearing mechanism when the power is furnished by an electric motor as the motor must travel at a relatively high rate of speed, compared to the rotation desired on the feed rolls of the tank, necessitating a train of several reduction gears of different sizes intermeshing to obtain the desired reduction before the shaft is rotated, and in order to substantially reduce this usual gearing and provide an independent operation of each tank, I have utilized an electric motor for directly operating separate drive shafts for each tank and driving each of the feed rolls from the drive shaft by worm and worm gears, thus providing a single pair of quiet running gears and an independent drive for each unit; and the following is a detailed description of the present embodiment of this invention illustrating the preferred means by which these advantageous results may be accomplished.

With reference to the drawings, 10 designates the tank which is supported by suitable frame work 11 having feet 12 to rest upon the floor or other suitable support. Within each tank there is a specially constructed metal frame which supports guide rolls 13, 14, 15 and 16 over which the traveling web 17 of textile fabric or the like is conducted from a package 18 rotating about an axis 19 to the package 20 rotated about the axis 21 or vice-versa through the bath contained in the tank 10.

This above described portion of the device is somewhat the usual construction, and the invention relates more particularly to the driving of the feed rolls 22 and 23 which are mounted upon suitable shafts 24 and 25. Shafts 24 and 25 are each similar and a clutch 27 is interposed in each shaft which is shown more fully in Fig. 2. Each shaft is rotated from the common drive shaft 28 extending at right angles to the parallel shafts 24 and 25 and connected thereto by means of a worm gear 29 mounted on each

shaft 24 and 25 intermeshing with worms 30 on the drive shaft 28.

An electric motor 31 has its axis of rotation axially aligned with the drive shaft 28 and is coupled thereto by a suitable coupling 32 for rotating the drive shaft 28. The coupling 33 is also interpositioned in the drive shaft 28 for convenience of assembly.

The worm and worm gears are enclosed in a housing 34 and 35 which also provides bearings 36 and 37 at each end thereof for the better support of the drive shaft 28. The housing 34 is liquid tight to contain a lubricant for the gears to assist the quiet operation of the device and prevent wear on the operating parts and also by having the lubricant entirely enclosed in this manner it cannot be spattered into the treating tank to soil the goods.

Each of the clutches 27 are provided with a collar 38 grooved as at 39, in which a ring 40 is located. Pins 41 and 42 extend from diametrically opposite sides of the ring, and in order to shift the clutch member 43 to and from engagement with its companion member 44, I have mounted a bracket 45 on the frame 46 of the device which supports an upwardly extending pivot pin 47 and on this pin I have mounted the hub member 48 from which there extends bifurcated arms 49, slotted as at 50 to engage the pins 41 and 42 of the ring 40, so that movement of the lever 51 will control the action of each of the rolls by moving the clutch into or out of operative position.

The members 48 are also provided with arms 52 extending laterally from the hubs and are connected by means of a link 53 so that when either of the levers 51 which extend from opposite sides of the machine are moved by the operator, the opposite clutch and lever is also moved, thus both clutches may be operated in unison from either side of the apparatus to accomplish direction of rotation desired.

In operation when the roll 22 is functioning to feed the web by drawing it from the package 20, the clutch 27 of the shaft 24 is in engagement to cause a drive of the package 18 and the clutch on the shaft 25 connected therewith to freely rotate. When it is desired to draw the cloth from package 18 to wind it upon package 20 the roll 23 is driven and the clutch on roll 22 will be positioned to permit the same freely to rotate, thus it will be observed that a shifting of a lever 51 at one side of the machine to throw the clutch into operative position will simultaneously cause a movement of the clutch on the other side of the machine to throw the clutch out of engagement, while the arrangement is such that there is an intermediate position in which both clutches are in neutral.

By the construction which I have above described an independent drive is provided

for each tank, thus eliminating the common connecting shaft for a series of tanks and permitting the operator to move freely and completely about each tank for inspection and manipulation of the work as desired. 70 Also by this construction I provide a thirty to one, or any desired reduction, in the speed of rotation by the spiral gears, enabling the feed roll to be driven directly from the electric motor shaft without the necessity for 75 providing a train of intermeshing spur gears, and also by enclosing the gears I am enabled to run them in lubricant and provide a more quiet and efficient drive and one in which the dye bath and work are free from soil. Also 80 as each jig is independent a constant or variable speed motor may be provided to run different tanks at different speeds, thus allowing far greater flexibility of action and manipulation of the work. 85

In some instances the web is reeled directly on the roll 22 or 23 and in such instances the use of the variable speed motor enables me to draw the web through the heating bath at a substantially constant speed if desired 90 thereby eliminating a variation in speed due to the varying diameter of the reeled package. Also by the use of a variable speed motor I am enabled to operate the tank at different speeds for different classes of work, 95 thus permitting the work to be passed through the tank slowly in some cases or faster for other classes of work.

The foregoing description is directed solely towards the construction illustrated, but I 100 desire it to be understood that I reserve the privilege of resorting to all the mechanical changes to which the device is susceptible, the invention being defined and limited only by the terms of the appended claims. 105

I claim:

1. In a dye jig, a tank, a pair of parallel feed roll shafts associated therewith, feed rolls on said shafts, a drive shaft at right angles to said shafts, worms on said drive 110 shaft at spaced points and a worm gear on each feed roll shaft meshing with a worm on said drive shaft, and clutch means interposed in each of said roll shafts for controlling the operation of the said shafts, a lever for the 115 clutch in each shaft, and a link connecting said levers for simultaneous operation.

2. In a dye jig, a tank, a pair of parallel feed roll shafts associated therewith, feed rolls on said shafts, a drive shaft at right 120 angles to said shafts, worms on said drive shaft at spaced points and a worm gear on each feed roll shaft meshing with a worm on said drive shaft, and clutch means interposed in each of said feed roll shafts for controlling 125 the operation of said shafts, a bracket adjacent each clutch, levers extending in opposite directions pivotally mounted on each bracket and each provided with arms to engage the clutch, and connecting arms extending from 130

said levers, and a link secured to said connecting arms for simultaneous operation of said levers.

3. In a dye jig, a tank, a pair of parallel feed roll shafts associated therewith, feed rolls on said shafts, a drive shaft at right angles to said shafts, worms on said drive shaft at spaced points and a worm gear on each feed roll shaft meshing with a worm on said drive shaft, clutch means interposed in each of said feed roll shafts for controlling the operation of said shafts, a bracket adjacent each clutch, shifter levers extending in opposite directions pivotally mounted on each bracket and provided with arms to engage the clutch, and connecting arms extending laterally, and a link secured to said connecting arms for simultaneous operation of said levers, and an electric motor having its axis of rotation in line with said drive shaft, and directly connected to said drive shaft, and a casing about said gears.

In testimony whereof I affix my signature.
RICHARD E. RUSDEN.
